UNITED STATES PATENT OFFICE

163,492

PORTABLE TRAFFIC SIGNAL

Scott B. Stetson, Stockton, Calif.

Application January 20, 1950, Serial No. 7,364

Term of patent 14 years

(Cl. D72—1)

To all whom it may concern:

Be it known that I, Scott B. Stetson, a citizen of the United States of America and a resident of the city of Stockton, county of San Joaquin, and State of California, have invented a certain new, original, and ornamental Design for a Portable Traffic Signal, of which the following is a specification, reference being had to the accompanying drawing, forming part of this application, in which

Figure 1 is a perspective view of a portable traffic signal, showing my new design,

Figure 2, a top plan view of the same, and Figure 3, a horizontal section taken along line 3—3 of Figure 1.

I claim:

The ornamental design for a portable traffic signal, substantially as shown.

SCOTT B. STETSON.
